Patented Mar. 25, 1975

234,595

VALVE BODY

Allen W. Cochrum, Houston, Tex., assignor to ACF
Industries, Incorporated, New York, N.Y.

Filed Dec. 19, 1972, Ser. No. 316,603

Term of patent 14 years

Int. Cl. D23—01

U.S. Cl. D23—32

FIG. 1

FIG. 2

FIG. 3

FIG. 4

FIG. 1 is a perspective view of a valve body showing my new design;

FIG. 2 is a side elevational view thereof;

FIG. 3 is a top plan view thereof, the bottom being the same as the top shown; and

FIG. 4 is a perspective view of a modified form of the valve body shown in FIG. 1, wherein the modification resides the smooth curvatures.

The broken line representation of valve actuators in FIGS. 1, 2 and 3 are for purposes of illustration only.

I claim:

The ornamental design for a valve body, as shown and described.
